CONFECTION

Samuel Rubin, Herman Rubin, and Paul Rubin,
Springfield, Mass.

Application May 26, 1950, Serial No. 10,231

Term of patent 14 years

(Cl. D82—2)

To all whom it may concern:

Be it known that, we, Samuel Rubin, Herman Rubin, and Paul Rubin, all citizens of the United States, and all residents of Springfield, Massachusetts, have invented a new, original, and ornamental Design for Confection, of which the following is a specification, reference being had to the accompanying drawings, forming a part thereof.

Fig. 1 is a side elevational view of a confection, showing our new design;

Fig. 2 is a front elevational view of the design shown in Fig. 1;

Fig. 3 is a plan view of the design shown in Figs. 1 and 2; and

Fig. 4 is an inverted plan view of the design shown in Figs. 1, 2 and 3.

We claim:

The ornamental design for confection, as shown.

SAMUEL RUBIN.

HERMAN RUBIN.

PAUL RUBIN.
